UNITED STATES PATENT OFFICE.

JOHN A. WHEERY, OF NEW ORLEANS, LOUISIANA, ASSIGNOR TO UNDERWOOD TYPE-WRITER COMPANY, OF NEW YORK, N. Y., A CORPORATION OF DELAWARE.

BILL SHEET.

Original application filed May 2, 1922, Serial No. 557,873. Divided and this application filed June 8, 1923. Serial No. 644,235.

This invention relates to a method of locating a succession of work-sheets for typing, and it relates also to an entry-sheet which may be typed according to the novel 5 method herein disclosed, and to a typewriting machine for carrying out such method.

Objects of the invention are to enable a succession of sheets to be typed rapidly, one after the other, and at the same time 10 to produce multiple copies.

A feature of novelty resides in inserting a first sheet from the rear, around beneath the platen, and up past the printing line, and subsequently inserting the sheets successively, one after the other, downwardly at the front between the platen and the top margin of the preceding sheet in slightly underlapping relation therewith, the platen being rotated so as to bring the successive 15 sheets down to the printing line, and to deliver the typed sheets at the rear of the platen, so that, as the platen is rotated, each newly-inserted sheet is guided, by the next preceding sheet, to pass downwardly and rearwardly between the platen and the usual paper-guiding devices associated with 20 the platen.

The novel entry-sheet may comprise a bill-part having joined thereto a record-part and 25 a stub-part to be folded into superimposed relation therewith, so that, by means of interleaved carbon-sheets, all of said sheet-parts may be typed at the same time and afterwards separated. More particularly, 30 the bottoms of the bill-part and record-part may be connected together along a transverse weakened line of detachment, along which the folding into superimposed relation may take place, and the stub-part may 35 be connected with one of the sides of the bill-part along a vertical weakened line of detachment, upon which the folding into superimposed relation may take place; and 40 each of said sheet-parts may have thereon 45 a form comprising suitable item-designations to be brought into alignment when the sheet is folded for typing, so that items typed will appear under the proper item-designations on each of the parts of the 50 sheet.

The novel typewriting machine forming a feature of the present invention is a revolvable-platen front-strike machine in which the front of the platen is the introductory

side and the rear of the platen is the delivery side, and adjustable side gages at the front of the platen form a chute for downwardly-inserted work-sheets, rolls being provided under the platen to co-operate therewith to feed the work-sheets rearwardly and to deliver the typed sheets at the rear of the platen, the platen being clear of paper-feeding devices above the printing line, so as to permit the ready introduction of a work-sheet downwardly by means of 55 the introductory chute and in underlapping relation to the previous work-sheet, a receptacle for the accumulation of the typed work-sheets being provided at the rear of the platen, and means being provided at the 60 front of the platen in proximity to and above the printing point for holding the work-sheet in printing position relatively to the platen, but in position to permit the downward introduction of a succeeding 65 work-sheet between the platen and the work-sheet held by said means.

This application is a division of my application filed May 2, 1922, Serial No. 557,873, (now Patent No. 1,548,498, dated 80 August 4, 1925).

Other features and advantages will hereinafter appear.

In the accompanying drawings, 85 Figure 1 is a diagrammatic end view of a platen-frame and some of the associated parts of the typewriting machine, and shows how the first and second sheets are inserted in carrying out the method, the first sheet being shown at the typing position.

Figure 2 is a similar view, showing a third sheet inserted from the front and being guided past the edge of the usual paper-apron by the preceding sheet as the platen is 90 rotated, to bring the last-inserted sheet down to the typing position.

Figure 3 is a similar view, showing how the successively typed sheets are delivered at the rear of the platen, and with the last 100 sheet inserted being brought to the typing position.

Figure 4 is a partly diagrammatic front elevation, on a reduced scale, of the platen-frame, platen and paper-guiding devices, an 105 entry-sheet being shown in broken lines.

Figure 5 is a plan view of one of the entry-sheets in flat condition, and shows the

side thereof which bears the forms for the record-part or ledger-sheet and for the stub-part of the bill.

Figure 6 is a perspective view, showing 5 one way of folding the entry-sheet, to bring its three parts into superimposed relation, and shows the ledger-sheet or record-part at the front, the bill-part at the back and the stub-part interposed between the bill-part 10 and record-part.

Figure 7 is a similar view, on a reduced scale, showing the bill-part at the front and the record-part or ledger-sheet at the back, with the stub-part interposed between the 15 bill-part and record-part.

In carrying out the method of the present invention, the first sheet A is inserted at the 20 rear of the revoluble platen 1 over a shelf or rear paper-table 2, and is guided around beneath the platen above the usual releasable feed-rolls 3 by means of the usual paper-apron 4, and is advanced to the front of the platen past the printing point thereon, indicated in Figure 1 by the raised type-head 5, where it may be held in position by 25 the usual wing-scales 6 (Figure 4), and by a front arm or finger 7 carrying a small roller 8 (Figure 1), being thus brought to the typing position, as shown in Figure 1. In 30 inserting this first sheet A from the rear, the feed-rolls 3 may be released and the sheet pushed around beneath the platen, or, in order to avoid releasing the feed-rolls, the sheet may be fed around to the typing 35 position by rotating the platen in the required direction by means of the usual finger-wheels 9 on the ends of the platen-axle 10, which is journaled in the end walls 11 of the platen-frame.

40 The sheet A may be adjusted by means of lateral guides or side-edge gages 12 having floor-portions 13, the lower edges of which are normally in proximity to the front of the platen above the printing line, as shown 45 in Figure 1, but which may be swung away from the platen by rotation about a transverse rod 14 along which the lateral guides or side-edge gages 12 are slidably adjustable, to accommodate sheets of different widths. 50 The gage-supporting rod 14 is fixed at its ends in brackets 15, which are secured upon the end walls 11 of the platen-frame. The outstanding lateral guides 12 enable all of the successively-inserted sheets to be inserted 55 and maintained in lateral alignment.

When the first sheet A has been typed, then a second entry-sheet B is inserted downwardly at the front of the platen between the lateral guides 12 over the floor-portions 60 13 thereof and between the platen and the top margin of the first sheet A, in slightly underlapping relation with the sheet A, as shown in Figure 1. The sheet B is pushed down just sufficiently that its lower margin 65 will be caught between the platen and the

back of the sheet A, which will be held against the sheet B by the usual paper-guiding devices, including the apron 4 and the wing-scales 6. The front roller 8, which is located in proximity to and above the printing point, is free from or clear of the platen, so as to hold the outer work-sheet A in printing position relatively to the platen while permitting the downward introduction of the succeeding sheet B past the roller 8, between 70 the sheet A and the platen, as shown in Figure 1. When the lower edge of the newly-inserted sheet B is in position to be gripped by the platen, the platen may be rotated in the direction indicated by the 75 arrows in Figures 2 and 3, by means of the finger-wheels 9, for bringing this second sheet B down to the writing position, while the first sheet A is fed around the platen to the rear, by means of the feed-rolls 3, under 80 the platen. As the platen is thus rotated, the lower edge of the front-inserted sheet B will be guided by the overlapping first-inserted sheet A down past the paper-guiding devices comprising the wing-scales 6 85 and front edge of the paper-apron 4. After the typing of the front-inserted second sheet B, a third sheet C is similarly inserted downwardly at the front of the platen at the back of the upper margin of the sheet B, 90 and again the platen is rotated, as indicated by the arrow in Figure 2, for bringing this third sheet C to the typing position, this latter operation being illustrated in Figure 2, in which the second sheet B is shown as 95 guiding the lower edge of the third sheet C past the upper or front edge of the paper-apron 4, while the third sheet C is being brought down to the typing position, and at the same time the first typed sheet A is 100 being delivered at the rear of the platen upon the inclined rear paper-table or receptacle 2.

The entry-sheets are thus successively inserted, one after the other, at the front of 105 the platen and brought down to the typing position, and, after being typed, are delivered at the rear of the platen, each upon the next preceding typed sheet, on the receptacle 2, as shown in Figure 3, which 110 shows the sheets A, B, C and D as having been typed and delivered upon the receptacle, while a typed sheet E is being delivered and a last-inserted sheet F is being brought to the typing position as the platen 115 rotates in the direction indicated by the arrow. The adjustable side-edge gages 12 together with their floor-portions 13, form an introductory chute at the front of the platen for the downwardly-inserted sheets, 120 as shown in Figures 1 and 4. The rear feed-rolls 3 form an abutment or stop at the rear of the platen to hold the accumulated typed sheets clear of the platen, as shown in Figure 3. The typed entry-sheets A, B, C, D, 125 130

etc., are permitted to accumulate, one upon another, in a stack upon the rear paper-table 2, as shown in Figure 3, until the stack has reached convenient proportions for handling, for example, fifty sheets, whereupon all of the typed sheets may be removed together.

In the novel typewriting machine for carrying out the novel method, no sheet-directing means at the front of the platen are required other than the adjustable chute-forming side gages 12, so that the front and top of the platen are otherwise clear of any device which might interfere with the downward insertion of the work-sheets or with the free manipulation and adjustment of the side gages. Also, as hereinbefore noted, the front of the platen above the printing line is clear of paper-feeding devices, and the small sheet-holding roller 8 is spaced from the platen, thereby providing for the unobstructed introduction of a work-sheet downwardly in underlapping relation to the previous work-sheet, as shown in Figure 1. Furthermore, and as shown in the drawings, this novel typewriting machine requires no line-spacing mechanism other than the finger-wheels 9, by means of which successively-inserted work-sheets may be quickly lowered to the typing position and the typed sheets delivered rearwardly of the platen upon the receptacle 2 there provided.

One of the entry-sheets, such as A, B, C, etc., appearing in Figures 1 to 4, inclusive, is shown in detail in Figures 5 to 7, inclusive. The entry-sheet comprises a bill-part 16, which may be a statement or invoice, a record-part 17, which may be a ledger-sheet, as indicated in the drawings, and a stub-part 18 for the bill-part 16. The lower or bottom edges of the bill-part 16 and of the record-part 17 are joined and are detachably connected along a transverse weakened line of detachment 19, indicated in the drawings as a line of perforations. In the form of the invention shown in the drawings, the bill-part 16 and record-part 17 are of the same width, and are also of the same length. The stub-part 18 is shown at the right side of the bill part 16, and is detachably connected therewith along a vertical weakened line of detachment 20, indicated in the drawings as a line of perforations. The lateral stub 18 is of the same length but of less width than the bill 16. Upon each of the sheet-parts, at the top thereof, there is an identifying designation, such designations being shown in the drawings as "Bill", "Ledger sheet", "Stub". Each of the sheet-parts also bears on its front or face a form which may comprise suitable item-designations arranged transversely in columns, each column being provided with the proper heading. In the particular entry-sheet shown in Figures 5 and 6 of the drawings,

the bill-part 16 is shown as provided with seven item-designations for corresponding item-receiving columns, while the record-part or ledger-sheet 17 is provided with the same item-receiving columns and item-designations similarly arranged from left to right; and the ledger-sheet 17 is also further provided, at the right side, with four additional column-designations and columns to receive additional data, which is to appear upon the ledger-sheet but not upon the bill, nor upon the stub, and which in some cases may be filled in upon the ledger-sheet at a later date. The lateral stub-part 18 is shown as provided with only three item-receiving columns and column-designations, which correspond to the last three columns and column-designations on the bill-part 16, and which also correspond to the fifth, sixth and seventh columns and column-designations on the ledger-sheet or record-part 17, as it is desired that the stub-part shall contain information corresponding only to a part of the information which is typed upon the bill-part 16 and record-part 17.

It is to be noted that the item-designations on the bill-part 16 are upon one side of the entry-sheet, while the item-designations for the record-part 17 and for the stub-part 18 are upon the other side of the entry-sheet. It is to be further noted that the item-receiving columns and column-designations on the bill-part 16 are in vertical alignment with the corresponding columns and column-designations on the record-part or ledger-sheet 17, and that the column-designations on each of these sheet-parts are arranged at the same distance from the tops or upper edges thereof, so that, when the bill-part 16 and the record-part 17 are folded over towards each other along the transverse perforated line 19, as indicated in Figure 6 or 7, the columns and item-designations on the bill-part 16 will be brought into correct register with the corresponding columns and item-designations on the record-part or ledger-sheet 17. It is also to be noted that the columns and column-designations on the stub-part 18 are in transverse alignment with the columns and column-designations on the bill-part 16, and that the columns and item-designations on the stub-part 18 terminate at the same distance from the vertical line of perforations 20 as do the columns and column-designations on the bill-part 16, so that, when the stub-part 18 is folded along the perforated line 20, the columns and item-designations on the stub-part will be brought into register with the corresponding columns and item-designations on the bill-part 16, as indicated in Figures 6 and 7; and also at the same time, obviously, will be brought into register with the corresponding columns and column-designations on the record-part or ledger-sheet 17 in the

folded condition of the entry-sheet. It follows, therefore, that, when the entry-sheet is folded from the flat condition thereof shown in Figure 5, along the perforated lines 19 and 20, the three sheet-parts will be superimposed with the corresponding columns and item-designations of all the sheet-parts in proper register, as will be clear from Figures 6 and 7, in which, however, the folded superimposed sheet-parts are shown as slightly separated for clarity of illustration.

Figures 6 and 7 illustrate, respectively, two different ways in which the flat entry-sheet shown in Figure 5 may be folded for bringing its three parts into superimposed relation for typing all these parts at the same time. In Figure 6 the stub-part 18 is shown as folded over upon the front of the bill-part 16, and the bill-part 16 and ledger-sheet 17 are folded together with the ledger-sheet 17 at the front while the bill-part 16 is at the back of the ledger-sheet 17, with the stub-part 18 interposed between the bill-part 16 and ledger-sheet 17. According to the manner of folding the entry-sheet shown in Figure 7, the stub-part 18 is folded over upon the back of the bill-part 16, while the bill-part 16 and ledger-sheet 17 are folded together with the bill-part 16 at the front and the ledger-sheet 17 at the back, with the stub-part 18 interposed between the bill-part 16 and the ledger-sheet 17. It is to be understood, of course, that carbon-sheets will be interleaved between the respective sheet-parts, so as to reproduce the items desired. In the manner of folding the entry-sheet shown in Figure 6, the ledger-sheet 17 will be an original or ribbon-copy while the bill 16 and its stub 18 will be carbon-copies. According to the manner of folding the entry-sheet shown in Figure 7, the bill 16 will be the original or ribbon-copy while the ledger-sheet 17 and bill-stub 18 will be carbon-copies. Obviously, if desired, the stub 18 could be folded over behind both the ledger-sheet 17 and the bill 16.

After the typing operation, the ledger-sheet 17 is detached and kept in the office 50 while the bill 16 together with its attached stub 18 is sent to the customer, who detaches the stub 18 from the bill 16, keeping the bill and returning the stub with his check, as is customary. The record-part or ledger-sheet 55 17 is shown as provided in its upper margin with holes 21 for use in filing the ledger-sheet.

In Figure 7 eight item-receiving columns are shown on the bill 16 and its stub 18, instead of the seven columns shown in Figures 5 and 6, thereby, in Figure 7, providing for an additional item which may also appear in a corresponding additional column on the ledger-sheet 17.

65 In making out in succession numerous

small bills, such as electric-light-bills, of which samples are shown in the drawings, gas-bills, and the like, which usually contain only one or possibly two lines of writing, and of which it is desired to have an 70 office record and also a returnable stub, it has been found that much time can be saved by the hereinbefore-described rapid method of typing and by the use of the three-part sheet shown in the drawings, and also by the 75 use of the novel typewriting machine shown in the drawings and hereinbefore described.

Variations may be resorted to within the scope of the invention, and portions of the improvements may be used without others. 80

Having thus described my invention, I claim:

1. A multiple-part entry-sheet comprising a record-part having suitable item-designations thereon, a bill-part joined at one of its 85 ends to one of the ends of the record-part and having item-designations thereon corresponding with said item-designations on the record-part, but on the opposite side of the sheet and in vertically- 90 reversed relation when the sheet is flat, the bill-part being foldable upon the record-part to bring the item-designations thereon into register with those on the record-part, and a stub-part joined along one of its sides to one 95 of the sides of the bill-part and having thereon item-designations corresponding to those on the record-part and bill-part, and on the same side of the sheet as the item- 100 designations on the record-part but in vertically-reversed relation thereto when the sheet is flat, the stub-part being foldable upon the bill-part to bring the item-designations thereon into register with the corresponding item-designations on the bill-part 105 and on the record-part, so that all of said sheet-parts may be typed in their folded superimposed relation and subsequently separated along the lines of folding between the sheet-parts. 110

2. A multiple-part entry-sheet comprising a record-part having a series of transversely-arranged item-designations thereon, a bill-part of the same width and same length as the record-part, and at its bottom detachably connected along a transverse weakened line of detachment with the bottom of the record-part, the bill-part having thereon a transverse series of item-designations corresponding to those on the record-part, but on the opposite side of the sheet and vertically reversed relatively to the record-part when the sheet is flat, the record-part and the bill-part being foldable along said weakened line into superimposed relation to bring the item-designations on said sheet-parts into register, and a stub-part at the right side of the bill-part of less width than but of the same length as the bill-part and detachably connected therewith along a vertical weak- 120 125 130

ened line of detachment and foldable along said vertical weakened line into superimposed relation with the bill-part and folded record-part, the stub-part having a series of 5 transverse item-designations thereon corresponding to those on the record-part and the bill-part, and on the same side of the sheet when the sheet is flat as the item-designations on the record-part and in vertically- 10 reversed relation thereto, said item-designa-

tions on the stub-part being brought into register with corresponding item-designations on the record-part and the bill-part when all of said sheet-parts are folded into superimposed relation for typing, so that all 15 of said sheet-parts may be typed together and subsequently separated along said weakened lines of detachment.

JOHN A. WHERRY.
